<img alt="A detailed technical diagram of a mechanical system, likely a pump or compressor assembly, labeled Fig. A. The diagram shows a complex network of pipes, valves, and mechanical components. Key parts include a pump unit at the bottom right with a motor (19), a valve assembly (11) with a handle, and a large cylindrical component (10). Above the pump is a vertical pipe section with valves (75, 76, 77, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROLLER FOR ELECTRIC MOTORS.

No. 883,078.

Specification of Letters Patent. Patented March 24, 1908

Application filed March 2, 1904, Serial No. 196,188. Renewed February 21, 1906. Serial No. 302,269.

To all whom it may concern:

Be it known that I, THOMAS E. BARNUM, citizen of the United States, residing at Milwaukee, in the county of Milwaukee and 5 State of Wisconsin, have invented a certain new and useful Improvement in Controllers for Electric Motors, of which the following is a full, clear, concise, and exact description reference being had to the accompanying 10 drawing, forming a part of this specification.

My invention relates to a controller for electric motors and preferably to such devices used in connection with electric motors for operating valves, my object being to provide 15 a controller for electric motors, whereby the direction in which the motor is run may be controlled and the motor automatically stopped a predetermined number of times throughout its range of operation.

20 A further object of my invention is to provide a controller for a valve operating motor by which it is impossible for the operator, either unintentionally or otherwise, to open the valve more than a predetermined portion 25 of its total opening at any one operation. To accomplish this object I provide means whereby, when the operating motor is started, it moves for a certain specified time and then automatically stops, it being then 30 necessary for the operator to again start the motor in order to open the valve further. I also provide means for reversing the direction in which the motor is adapted to run.

In the accompanying drawings, in which 35 like numerals refer to like parts throughout the several figures, Figure 1 is an elevation showing a solenoid switch for controlling the motor circuit, an indicating lever controlling the solenoid switch and a reversing 40 switch; Fig. 2 is an elevation of the means for automatically stopping the motor, showing the valve in section; Fig. 3 is a diagrammatic view of the circuit arrangement; and, Fig. 4 is a diagrammatic view of the circuit 45 arrangement for a modification.

In the construction which I have worked out as the preferable form of my invention, I provide a valve which may be of any construction, but in the present instance is 50 shown as having a body 2, in which are adapted to operate the gates 3. The gates are connected to a carrier 4 and are adapted to be opened and closed by the movement thereof. Attached to the upper portion of

the body is a valve cover 5 carrying at its 55 upper end a stuffing box 6, through which is adapted to operate the valve stem 7 threaded at its lower end, into the carrier 4. At the upper end of the valve stem and operating in the stuffing box 6 is formed a 60 shoulder 8, which bears on one side against the valve body and on the other side against the stuffing box, thereby preventing the valve stem from moving laterally. Upon the upper end of the valve stem is keyed a 65 worm wheel 9 adapted to be rotated by a worm gear 10, secured upon the shaft of the motor. The valve stem 7 is connected at its upper end by a coupling 11 to a threaded commutator shaft 12, journaled in the 70 bearings 13 and 13, suitably mounted upon the commutator 14. A cross head 15 is threaded on the commutator shaft and carries brushes 16 and 17 electrically connected to each other, and brushes 18 and 19 also 75 electrically connected to each other but insulated from the brushes 16 and 17. The brushes 16 and 17 are adapted to pass over and make contact with the contact bars 20 and 21, respectively, and the brushes 18 and 80 19 are adapted to pass over and make contact with the contact bar 22, and the series of contact buttons 23, 24, 25, and 26 mounted upon the commutator 14.

A solenoid switch 27 is adapted to control 85 the motor circuit and is provided with a bridging contact 28 to connect together the terminals 29 and 30. The solenoid of this switch is also connected preferably by an insulating connecting link 31, with the pivoted pawl 32, having a catch 33 adapted to engage notches 34 on a segmental extension 35 of a pivoted operating lever 36 which lever also serves to indicate the position of the valve and will therefore hereafter be designated as the indicating lever. The lever 36 is provided with a brush adapted to sweep over and make contact with the contact buttons 37, 38, 39, 40 and 41. This series of buttons are so spaced that the brush on the 100 indicating lever will have to pass freely off of one button before making connection with the next, so that under no circumstances will it be possible for the brush to bridge from one live button to the next. A double throw 105 knife switch having blades 42 and 43 and terminals 44, 45, 46, 47, 48, 49, 50, 51, 52 and 53, is mounted upon the same board as the

solenoid switch and indicating lever and controls the direction in which the motor is run.

Referring now to the diagrammatic view shown in Fig. 3, the main 54 is connected by conductor 56 with the terminal 29 of the solenoid switch. One terminal of the winding of the solenoid switch 27 is connected by conductor 57 with the terminal 29 and 10 the opposite terminal is connected through the lamp switch 58 by conductor 59, with the indicating lever 36. The opposite terminal 30 of the solenoid switch is connected by the conductor 60 with one terminal of the 15 field winding of the motor, the opposite terminal of which is connected by conductor 61, with the terminal 44 of the double throw switch lever. The terminal 44 is connected by conductor 62 with the terminal 47 of the 20 switch lever. One brush of the armature of the motor is connected by conductor 63 with the terminal 46 of the switch lever, and the opposite brush is connected by conductor 64 with the terminal 45 of the switch 25 lever. The terminal 45 is cross connected by conductor 65 with the terminal 50 and the terminal 46 is cross connected by the conductor 66 with the terminal 51. The terminal 53 of the switch lever is connected by 30 conductor 67 with the terminal 48 and this terminal in turn is connected with the opposite side 55 of the main line. The contact button 37 is connected by conductor 68 with the contact bar 21, and the contact buttons 35 38, 39, 40 and 41 are respectively connected by conductors 69, 70, 71 and 72, with the contact buttons 23, 24, 25, and 26 of the valve commutator. The contact bars 20 and 22 of the valve commutator are connected respectively by conductors 73 and 74 40 with the terminals 52 and 49 of the double throw knife switch. By this arrangement of circuits, the operator cannot open the valve more than one quarter of its travel at a time, 45 and cannot start the valve motor in the same direction to open the valve further until the motor has stopped after moving the valve one quarter of its travel. It is possible, however, to close the valve from any position 50 to the full closed position in one continuous motion. The connections of the motor are so arranged that when the double knife switch is thrown up the motor will rotate so as to open the valve and when the double 55 throw knife switch is thrown down, the motor armature connections will be reversed, so that the motor will rotate to close the valve.

The operation of the invention is as follows: 60 Assuming the valve in the closed position, as would be indicated by the commutator cross head resting on the contact button 23 and the indicating lever 36 being on the button 37, if the operator desires to open the valve 65 the knife switch is thrown up and the indicat-

ing lever 36 is moved to the button 38. When the brush on the indicating lever makes contact with the button 38, the circuit through the solenoid winding is closed and the current will flow from the main 54, to the terminal 29, of the solenoid switch, through the conductor 57 through the windings of the solenoid across the lamp switch 58, through conductor 59 to the indicating lever 36. From this point the current flows through the indicating lever to the button 38, through the conductor 69, to the button 23 on the valve commutator, from thence through the brushes 18 and 19 to the contact bar 22, through the conductor 74 to the terminal 49 of the knife switch through the knife switch blade to terminal 48 and thence to the opposite side 55 of the mains. The winding of the solenoid switch is thus energized, closing the circuit to the series motor in such a way that 85 the motor will rotate to open the valve. Current for the motor will flow from the main 54 to terminal 29, across the bridge 28 to terminal 30, through conductor 60, through field winding of the motor, through conductor 61 to terminal 44 of the knife switch, through conductor 62 to the terminal 47 of the knife switch, across the knife switch blade to terminal 46, through conductor 63, through the motor armature and conductor 95 64, to terminal 45 of the knife switch, from thence through conductor 65 to terminal 50 of the knife switch, and across the blade of the knife switch to terminal 48, thence to the opposite side 55 of the main line. The circuit thus closed, the motor will operate to open the valve and by means of the threaded shaft 12 of the commutator, the cross head of the same would be moved in a straight line over the contact buttons. As soon as the 100 commutator cross head has moved so that the brush 19 of the same leaves the contact button 23, the circuit of the solenoid switch will be open and the solenoid switch will open and stop the motor. When the solenoid switch is closed it moves the pivoted pawl 32 through the link 31, and the point 33 of the pawl engages with one of the notches 34 of the indicating lever. The indicating lever is thus interlocked positively so that it is 115 not possible to move the same. The notches 34 also insure the movement of the lever to its proper position on the button, as the switch will not close unless the point 33 of the pawl is in a position to drop down into the notch. 120 When the solenoid switch is open, the indicating lever is not locked, so that it is possible to move the same to the next button provided it is desired to open the valve another one quarter travel. To open the valve 125 fully, the cycle of operations would have to be gone through for the succeeding buttons 39, 40, and 41, one after the other, the operator always being obliged to allow the motor to stop before being able to start it again. The 130

valve commutator thus acts as a limit switch, and it is impossible for the operator to try to open the valve too far, as for either the full open or full closed position of the valve, circuit to the solenoid switch is opened and if the operator throws the knife switch in the wrong direction, circuit to the solenoid cannot be closed on any button of the indicating lever.

Assuming that the operator wishes to close the valve after it has been opened one quarter of its travel, the brush of the indicating lever would be on the button 38 and brush 19 of the commutator cross head would be on the contact button 24, the other brushes being on the contact bars 20, 21, and 22. In this position, with the knife switch thrown down, the solenoid switch circuit is not closed, due to the fact that the circuit to contact 49 is opened and it will be necessary for the operator to move the indicating lever back to the button 37 to indicate the closed position of the valve in order to complete the solenoid circuit. When the indicating lever is so moved the circuit to the solenoid switch will be closed and the current will flow from the main 54 to terminal 29, through conductor 57, through the solenoid winding across the lamp switch 58, through conductor 59, to the indicating lever 36. From this point the current will flow through the indicating lever to the button 37, through conductor 68 to the contact bar 21, thence through the brushes 17 and 16 to the contact bar 20, thence through the conductor 73, to terminal 52. From this point the current will flow through the knife switch blade to the terminal 53, through the conductor 67 to terminal 48, and thence to the opposite side 55 of the line. The solenoid switch circuit is thus closed and the winding energized to operate the switch to close the circuit to the motor field, and the knife switch being thrown down, the motor armature terminals will be reversed with reference to the lines, so that the motor will rotate in a direction opposite to that before, and close the valve. The motor circuit may now be traced from the main 54 to the terminal 29 of the solenoid switch across the bridge 28 to the terminal 30, thence through the conductor 60, through the motor series field, through conductor 61, to terminal 44 of the knife switch, through the knife switch blade to terminal 45, through the conductor 64, through the motor armature, through the conductor 63, to the terminal 46 of the knife switch. From here it will pass through the conductor 65, to the terminal 51, of the knife switch, across the switch blade to the terminal 53, through conductor 67 to the terminal 48 and thence to the opposite side 55 of the main circuit. The motor will continue to operate to close the valve until the brushes carried by the commutator cross head will have moved off

the contact bars 20 and 21, when the circuit to the solenoid switch will be opened and the valve motor stopped.

As illustrated in Fig. 4, I have shown a modification whereby the motor is operated in both directions step by step. In this construction, the commutator bar 21 is replaced by four buttons 75, 76, 77, and 78. The buttons 76, 77 and 78 would be cross connected by conductors 79, 80 and 81, respectively, with the buttons 23, 24 and 25, respectively, and the button 75 would be connected by the conductor 68 with the contact button 37. By this arrangement, the operation of the device would be as follows: Assuming that the commutator cross head is in its lowest position, corresponding to the closed position of the valve, and the indicating lever 36 is on contact button 37, to open the valve, it is necessary, as before, to throw the knife switch up and move the indicating lever to contact button 38 when the valve motor will be operated and the valve commutator cross head moved up to the button 24. If it is desired to open the valve fully, this operation would have to be gone through with for the other buttons 39, 40, and 41. If it is desired to close the valve, the knife switch would be thrown down in the manner as previously described, and assuming that the operator has opened the valve fully, the indicating lever would be resting on the contact button 41, and the cross head of the commutator will be at the top, the brushes 18 and 19 resting on the dead buttons at the top and the brushes 16 and 17 resting on the contact bar 20, and the contact button 78, respectively. To close the valve one quarter of its travel, therefore, the knife switch being thrown down, the indicating lever 36 would be moved to the contact button 40 and the current would then flow from the main 54 to the terminal 29, through the conductor 57, through the winding of the solenoid 27 across the lamp switch 58, through the conductor 59, to the indicating lever 36. From the indicating lever it would flow through the conductor 71 to the contact button 25, through the conductor 81 to the contact button 78, through the brushes 17 and 16 to the contact bar 20, and from thence through the conductor 73 to the contact point 52, across the knife blade switch to the contact point 53, through the conductor 67 to the contact point 48 and thence to the opposite side 55 of the supply mains. The solenoid switch is, therefore, closed and the motor will be operated to close the valve until the cross head and the brush 17 will have been moved off the contact button 78. When this happens, the circuit to the solenoid switch is opened and the motor stopped and to continue to close the valve it will be necessary to move the indicating lever 36 over each of

the remaining buttons 39, 38 and 37, allowing the motor to stop each time.

While I have described the preferred form of my invention, as having the commutator bar 20 of one piece, it will be readily seen that this bar may be made of separate buttons connected to one another, said buttons being also cross connected with the buttons 23, 24, 25, and 26, etc., and by this arrangement the motor controller may be changed from one form to the other very readily by breaking the connections of the buttons with the contact buttons 23, etc.

The construction, as herein set forth, it will be seen, automatically stops the motor after the valve has reached its predetermined point, and the indicating lever serves to indicate or show the exact position in which the valve gate stands.

While I have shown four movements of the valve, and the corresponding buttons for these movements, it will be readily understood that I do not wish to limit myself to this number of movements, as an increase in the number of contact buttons, both for the indicating lever and for the commutator cross head would increase the number of movements the valve may have, and it is customary to have at least twenty movements of the valve, thereby giving a greater control over the amount of fluid passing through said valve.

Having described my invention what I claim as new and desire to secure by Letters Patent is:

1. In a motor controller, the combination with a motor, of means for controlling the direction of operation thereof, means for operating the motor in successive periods of time throughout its range of operation, means for automatically stopping the motor at the end of each period, and means to prevent the operation of the motor for more than one period at a time.

2. In a motor controller, the combination with a motor, of means for controlling the direction of operation of the same, means for dividing its operation into a number of stages, and means for preventing the operation of the motor for more than a single stage with a single operation of the controller and means to prevent more than one operation of the controller at a time.

3. In a motor controller, the combination with a motor, of manually operated means for controlling the direction of operation of the same, means for dividing the operation of the motor into stages, and means for insuring the stoppage of the motor at the end of each stage previous to again proceeding on the succeeding stage.

4. In a motor controller, the combination with a motor, of a manually operated contact switch and an automatically operated switch

for opening and closing the motor circuit, said switches being functionally connected to permit the operation of the manual switch only when the automatic switch is in a certain relation thereto.

5. In a motor controller, the combination with a motor, of an electromagnetic switch for controlling the same and means operated at predetermined periods for operating said switch.

6. In a motor controller, the combination with a motor, of an electromagnetic switch for controlling the same, means operated at predetermined periods for operating said switch, and means for controlling the direction of operation of the motor.

7. In a motor controller, the combination with a motor, of a single switch for controlling the circuit of the same, means for closing said switch, means for automatically opening the same when the motor has operated for a predetermined length of time and independently operated means for controlling the direction of operation of the motor.

8. In a motor controller, the combination with a motor, of means for operating the motor in one direction for certain definite periods of time throughout its range of operation and for operating the motor continuously in a reverse direction throughout its range of operation and independently operated means for controlling the direction of operation of the motor.

9. In a motor controller, the combination with a motor, of a switch for controlling said motor, means for closing said switch and means for automatically opening the same when the motor has operated for a predetermined period, said switch preventing a further operation of said first mentioned means while it is closed.

10. In a motor controller, the combination with a motor, of a switch for controlling the same, means for closing the switch, means for automatically opening said switch a predetermined number of times throughout the range of operation of the motor and independently operated means for controlling the direction of operation of the motor.

11. In a motor controller, the combination with a motor, of an electrically operated switch for controlling the same, a manually operated switch for closing the circuit to said switch to close the same, and an automatically operated switch opening said circuit when the motor has operated for a predetermined period.

12. In a motor controller, the combination with a motor, of an electrically operated switch for controlling the same, a movable member for closing the circuit to said switch to close the same, means for automatically opening said circuit when the motor has operated for a predetermined period, and

means operated by said switch to prevent said lever from being moved while the motor is operating.

13. In a motor controller, the combination 5 with a motor, of a switch for controlling the same, means for closing said switch a predetermined number of times throughout the range of operation of the motor, means for automatically opening the same after the 10 motor has operated for a predetermined period and independently operated means for controlling the direction of operation of the motor.

14. In a motor controller, the combination 15 with a motor, of an electromagnetic switch for controlling the same, means for closing the same a predetermined number of times throughout the range of operation of the motor, and means for automatically opening 20 the same after each operation of said first mentioned means.

15. In a motor controller, the combination with a motor, of an electromagnetic switch 25 for controlling the same, means for closing said switch, and means operated by the mechanism driven by said motor for automatically operating the same.

16. In a motor controller, the combination 30 with a motor, of a valve operated thereby, an electrically operated switch for controlling the same, means for closing the circuit to said switch a number of times throughout the range of operation of the motor, means operated by said valve for automatically 35 opening the circuit to said switch when the motor has operated for a predetermined period, and means for controlling the direction of said motor.

17. In a motor controller, the combination 40 with a motor, of a valve driven thereby, an electrically operated switch for controlling said motor, a lever for closing the circuit to said switch, a predetermined number of times throughout the range of operation of the 45 motor, means operated by said valve for opening the circuit to the switch after the motor has operated for a predetermined period, and means for controlling the direction of operation of the motor, said lever also indicating the position of the valve.

18. The combination with a motor, of a valve driven thereby, an electrically operated switch for controlling said motor, a lever for closing the circuit to said switch a predetermined number of times throughout the range of operation of the motor, a switch operated 55 by said valve for opening the circuit to said electrically operated switch after the motor has operated for a predetermined period and 60 a reversing switch for controlling the direction of operation of the motor.

19. The combination with a motor, of a valve operated thereby, an electrically operated switch for controlling said motor, a lever

adapted to sweep over a series of contacts for 65 closing the circuit to said switch a predetermined number of times throughout the range of operation of the motor, a switch for controlling the direction of operation of the motor, and a commutator operated by said 70 valve and adapted to pass over one set of contacts electrically connected with said first mentioned contacts, and over a second set of contacts electrically connected with said direction controlling switch. 75

20. The combination with a motor, of a valve driven thereby, an electrically operated switch for controlling said motor, a lever for closing the circuit to said switch a predetermined number of times throughout the 80 range of operation of said motor, means operated by said valve for opening the circuit to said switch after the motor has operated for a predetermined period, means for controlling the direction of operation of the motor, 85 and means operated by said electrically operated switch for preventing the movement of said lever while the motor is in operation.

21. In a system for controlling the operation of motors, in combination, a motor, a 90 double throw switch for controlling the direction of operation of the motor, a solenoid switch for closing the circuit to the motor, an indicating lever in series in the solenoid circuit, and movable to contact points electrically connected to contacts on a commutator, a brush on said commutator operatively connected to the motor, to move on and off of the contact points on said commutator to make and break the circuit through the solenoid switch, and means operated by said solenoid switch to lock said indicating lever 95 in position. 100

22. In a system for controlling the operation of motors, in combination, a motor, a 105 switch for controlling the direction of operation of the motor, a solenoid switch for closing the motor circuit, a commutator consisting of contact plates and points and a brush moved over the same by means connected to the motor, an indicating lever movable to contact points electrically connected to the contact points on the commutator to close the solenoid switch circuit through the brush on said commutator, and locking 110 means for said indicating lever operated by said solenoid switch. 115

23. In a system for controlling the operation of motors, in combination, a motor, a switch for controlling the direction of operation of the motor, a solenoid switch for closing the circuit to the motor, means for closing the circuit to the solenoid switch at regular intervals for definite periods, while the motor is operating in one direction, and 120 means for closing the circuit to the solenoid switch continuously while the motor is operating in the opposite direction. 125

24. In a system for controlling the operation of motors, in combination, a motor, a double throw switch to control the direction of operation of the motor, a solenoid switch for closing the circuit through the motor, an indicating lever in series in the circuit through said solenoid switch and movable to contact points electrically connected to a commutator, to close the circuit to the solenoid switch through said commutator, and means carried by the solenoid switch adapted to engage with the indicating lever to lock it in position when the motor circuit is closed. 55 60
- 10 25. In a system for controlling the operation of a motor, in combination, a motor, a switch for controlling the direction of operation of the motor, a solenoid switch for making and breaking the circuit to the motor, means for making and breaking the circuit through the solenoid switch at successive stages in operating the motor in one or both directions, and means carried by the solenoid switch for locking the system when the circuit through the solenoid switch is made. 65 70
- 15 26. In a system for controlling the operation of motors, in combination, a motor, a switch for controlling the direction of operation of the motor, a solenoid switch for making and breaking the circuit to the motor, an indicating lever in series in the solenoid switch circuit and movable to contact points, an arrangement of circuits connecting said contact points with means by which the circuit to the solenoid switch may be closed for predetermined periods and broken after that period on the movement of the indicating lever to the successive contact points, and means for locking the system while the circuit through the solenoid switch is closed. 75 80
- 20 30 35 40 45 50 27. The combination with a motor, of a valve driven thereby, a switch for controlling the direction of operation of the motor, a solenoid switch for closing the motor circuit, an indicating lever movable to contact points electrically connected to contact points on a commutator, a brush for said commutator operatively connected to said valve and adapted to close the circuit to the solenoid switch for predetermined periods, only on the movement of the indicating lever to the successive contact points, to operate the 90 95
- motor to drive the valve in one direction, in stages, throughout its range of movement in that direction, means for keeping the circuit to the motor closed to drive the valve continuously in the opposite direction for any part or all of its range of movement in that direction, and means for locking the indicating lever in position while the circuit to the solenoid switch is closed. 60
28. In a system for controlling the operation of motors, the combination of a motor, means for setting the motor for a definite range of operation, means for automatically stopping the motor after it passes its range of operation, means for controlling the direction of operation of the motor, and means for electrically interlocking the system to prevent the motor from being operated in the wrong direction when set for operation through a predetermined range. 65 70
29. In a system for operating motors, the combination with a motor, of means for setting the motor for a definite range of operation, means for automatically stopping the motor after it has passed through the range of operation for which it is set, and means for setting the motor for operation in either direction, said means being interlocked with the other elements of the system to prevent the motor from being started in a wrong direction when set for operation through a predetermined range. 75 80
30. In a system for controlling electric motors, the combination with a motor, of means for setting the motor for a definite range of operation; means for automatically stopping the motor after it has passed through the range of operation for which it is set, means for setting the motor to operate in either direction, and means for electrically interlocking the elements of the system to prevent the motor from being operated in the wrong direction when set for operation through a predetermined range. 85 90 95

In witness whereof, I have hereunto subscribed my name in the presence of two witnesses.

THOMAS E. BARNUM.
